D. C. EN EARL.

KEY RING LOCK.

APPLICATION FILED NOV. 7, 1913.

1,092,031.

Patented Mar. 31, 1914.

UNITED STATES PATENT OFFICE.

DARIUS COMSTOCK EN EARL, OF DENVER, COLORADO.

KEY-RING LOCK.

1,092,031.

Specification of Letters Patent. Patented Mar. 31, 1914.

Application filed November 7, 1913. Serial No. 799,761.

To all whom it may concern:

Be it known that I, DARIUS COMSTOCK EN EARL, a citizen of the United States, and a resident of Denver, in the county of Denver and State of Colorado, have made certain new and useful Improvements in Key-Ring Locks, of which the following is a specification.

My invention relates to improvements in locks for key rings, hasps, and other pivoted members, and it consists in the combinations, constructions, and arrangements herein described and claimed.

An object of my invention is to provide a lock which is in the nature of a puzzle that may be readily operated by one who understands the construction and purpose of the lock, but which is exceedingly difficult to open by one who does not understand the operation.

A further object of my invention is to provide a lock of the type above described which needs no key, but which is operated by holding the parts in certain positions, these certain positions being necessary on account of balls which form coöperating members of the locking mechanism, and which must be retained in certain positions in order to effect the opening of the lock.

A further object of my invention is to provide a device of the type described having few parts and which can therefore be cheaply made.

Other objects and advantages will appear in the following specification and the novel features of the device will be particularly pointed out in the appended claims.

My invention is illustrated in the accompanying drawings forming part of this application in which—

Figure 1 is a side view of a key ring provided with my improved lock, Fig. 2 is an enlarged view of the device, the outer shell being shown in section, Fig. 3 is a view similar to Fig. 2, the lock being shown open, Fig. 4 is a section along the line 4—4 of Fig. 2, looking in the direction of the arrow, Fig. 5 is a section along the line 5—5 of Fig. 2, Fig. 6 is a section along the line 6—6 of Fig. 2, the sleeve being omitted. Fig. 7 is a side view of the hinged portion, Fig. 8 is a perspective view of a stop member. Fig. 9 is an enlarged section through the lock showing one position of the parts, and Fig. 10 is a similar section showing another position of the parts.

In carrying out my invention I may make use of a ring such as that shown at 1. The end of the ring is provided with an L-shaped extension 2, which forms a locking member. A shoulder 2^x forms a stop member for the shell as hereinafter explained.

Hinged at 3 to the body portion 1 of the ring is a locking member 4. This is provided with an enlarged cylindrical portion 4^a having a circular groove 4^b and a wedge-shaped groove 4^c extending at right angles to the groove 4^b. At one end of the groove 4^c is a transverse bore 4^e arranged to receive the laterally extending stem 5^a of a stop member 5, which is pressed upon by a spring 6. On each side of the groove 4^c are pockets like those shown at 7 in Fig. 5. The enlarged portion 4^a of the hinged member has an L-shaped extension 4^x arranged to cooperate with the extension 2 of the member 1 to lock the parts together as shown in Fig. 2.

At 8 I have shown a slidable sleeve or shell which is provided with an inner annular groove 8^a smaller than the groove 4^b. The widths of these two grooves 4^b and 8^a are substantially in the ratio of 3 to 2, thus the groove 4^b in the part 4^a may be three-eighths of an inch in width, while the groove 8^a may be two-eighths of an inch. The sleeve or shell is arranged to bear on the outside of the enlarged portion 4^a. It is provided with an inwardly extending tongue 8^k and with a shoulder 8^s. It will be observed that the provision of the groove 4^b leaves a flange 4^d adjacent to the groove.

From the foregoing description of the various parts of the device the operation thereof may be readily understood. In assembling the device steel balls 9 are placed in the pockets 7, the member 4^a being held in the position shown in Fig. 7. The shell or sleeve 8 is now slipped over the end 4^x and rotated until the tongue 8^k comes into registration with the stop member 5. The latter is pushed downwardly until the end of the tongue 8^k has passed over the end of the member 5 far enough to hold it down, while the sleeve is being pushed still farther on, *i. e.*, toward the hinge 3. The sleeve is now in the position shown in Fig. 3. The hinged member is now swung downwardly so as to engage the locking member 2. The sleeve 8 is shifted away from the hinge 3 over the locking member 2, as shown in Fig. 2. If now the key ring is inverted or

shaken the balls will pass out of the pockets and will roll down the aligned grooves into some such position as that shown in Fig. 5. It is now impossible to pull back the sleeve, 5 since the balls project partly into the groove 8^a in the sleeve. A person who is given the lock to release will find it exceedingly difficult to do so because he does not understand the construction of the same.

10 It will be noted that I have placed certain indicating marks 10 on the end of the sleeve and other indicating marks 11 on the member 4. The marks on the shell may indicate the position of the tongue 8^k, while 15 the marks on the member 4 indicate the relative positions of the pockets 7. Now when it is desired to open the device the key ring is held in substantially the position shown in Fig. 7 in which position it will be observed 20 that the pockets are on the upper side of the member 4^a. The first act in connection with opening the device is to slide the sleeve 8 as far as it will go away from the hinge 3. The position of the parts after this movement 25 is shown in Fig. 9, from which it will be observed that the balls will now be held between the edge of the groove 4^b farthest from the hinge 3 on one side and the edge of the groove 8^a nearest to the hinge 3 on 30 the other. The sleeve is now turned in a clockwise direction when looking from the end of the sleeve nearest to the hinge 3. This will cause the balls to be carried along 35 in the groove 4^b around toward one of the pockets 7 at a rate which is approximately one-half as fast as the sleeve itself is turning. Now when the pocket is reached the sleeve is moved in the opposite direction, 40 *i. e.*, toward the hinge 3 and the ball will drop in the pocket and remain there. It will be observed that the tongue 8^k prevents the sleeve from further movement by its engagement with the flange 4^a, this bringing the ball to substantially the center of the 45 groove 4^b where it freely drops into the pocket 7, as above stated. As soon as the sleeve is moved toward the hinge as indicated in Fig. 10, the second ball, which, of course was being carried around with the 50 first ball is now free and immediately drops to the bottom of the groove 4^b. With the parts in the position shown in Fig. 10, *i. e.* with the tongue 8^k bearing against the flange 4^a, and the pocket 7 which contains one of 55 the balls in a position such as that shown in Fig. 7 on the upper side of the device, so as not to dislodge the ball already pocketed, the sleeve is rotated so as to bring the tongue 8^k in such a position that its 60 angular distance around to the spring-pressed stop member 5 measured in a direction away from the pocketed ball (not past it) is twice that of the distance of the ball in the bottom of the groove to the spring- 65 pressed stop member 5. This can be ascer-

tained by noting the mark which indicates the position of the tongue. The sleeve is again pressed into the position shown in Fig. 9 and is rotated in a clockwise direction looking from the hinge, *i. e.*, in the 70 opposite direction to that in which it was rotated at first in order to pocket the first ball. The second ball which was at the bottom of the groove will now be carried upwardly with the sleeve, but the sleeve will 75 rotate twice as fast. The second ball will be carried past the unoccupied pocket owing to the friction between the edges of the sleeve and the body portion and will be forced against the spring stop member 5. 80 This is provided with a beveled portion 5^x, which will allow the sleeve to ride on top of the spring-pressed portion thus forcing it downwardly. If the positions of the tongue 8^k and of the ball in the bottom of the 85 groove were correctly gaged the tongue 8^k will arrive at the spring-pressed member 5^x at the same time that the second ball does. The second ball and the tongue being in alignment, and the stop member 5 being 90 pressed downwardly by the ball, and the pocketed ball being out of the way, the sleeve may now be slipped forwardly, *i. e.*, toward the hinged end, the tongue 8^k on the sleeve 8 entering the groove 4^c, and when 95 it is slipped far enough the device may be opened up, as shown in Fig. 3.

I claim:—

1. In a locking device, a stationary member, a hinged member arranged to engage said stationary member, said hinged member being provided with an annular groove and having an inwardly extending pocket communicating with said groove and a longitudinal groove intersecting said annular groove, 100 a sleeve arranged to slide on said hinged member and having a groove arranged to register with said first named groove and being provided with a tongue arranged to enter said longitudinal groove, said sleeve 105 being rotatable on said hinged portion to bring said tongue into registration with said longitudinal grooves, and balls disposed within said annular grooves.

2. In a locking device for key rings and the like, the combination with a body portion having an L-shaped extension, of a hinged member having an L-shaped extension arranged to engage said first named L-shaped extension, said hinged member being 120 provided with an annular groove and having a longitudinal groove intersecting said annular groove, a spring-pressed stop member carried in said longitudinal groove, a sleeve rotatably mounted on said hinged member 125 and having a longitudinal sliding movement relative thereto, said sleeve being provided with an internal groove arranged to register with said first mentioned groove, said hinged member being provided with a pocket con- 130

tiguous to said first mentioned groove on each side of said spring-pressed member, a tongue carried by said sleeve and adapted to register with said longitudinal grooves, and 5 balls disposed within said annular grooves.

3. In a locking device, a fixed member, a hinged member arranged to engage said fixed member, said hinged member being provided with an annular groove and having inwardly 10 extending pockets communicating with said groove, said hinged member having a longitudinal groove, a sleeve arranged to slide longitudinally on said hinged member and to rotate thereon, said sleeve being provided with 15 a tongue arranged to enter said longitudinal groove, and balls disposed in said first named grooves and arranged to enter said pocket thereby permitting the longitudinal movement 20 of the sleeve relative to the hinged member.

4. In a locking device, a fixed member, a hinged member arranged to engage said fixed member, a sleeve slidably and rotatably mounted on said hinged member and adapted 25 to slide over a portion of said fixed member, said hinged member and said sleeve being provided with registering grooves, and balls carried in said grooves, said hinged member being provided with pockets communicating 30 with its groove.

5. In a locking device, a fixed member, a hinged member arranged to engage said fixed member, a sleeve slidably and rotatably mounted on said hinged member and adapted 35 to slide over a portion of said fixed member, said hinged member and said sleeve be-

ing provided with registering grooves, balls carried in said grooves, said hinged member being provided with pockets communicating with its groove, said hinged member having 40 a longitudinal groove intersecting the first named groove, and a spring-pressed stop member disposed in said longitudinal groove and arranged to project into said first named groove, one edge of said spring-pressed stop 45 member being provided with a beveled portion for engagement by the balls.

6. In a locking device, a fixed member, a hinged member arranged to engage said fixed member, said hinged member being provided 50 with an annular groove and having a flange adjacent to the groove and a longitudinal slot or groove at right angles to and intersecting said first named groove, a sleeve or shell slidably and rotatably disposed on said 55 hinged member and being provided with a tongue arranged to engage said flange in one position, said tongue being arranged to register with said longitudinal groove in another position, said sleeve being provided 60 with an inner annular groove arranged to register with said first mentioned groove, balls disposed in the registering grooves, said hinged member being provided with pockets for receiving the balls, thereby retracting 65 them from the groove in the sleeve and permitting the slidable movement of the latter.

DARIUS COMSTOCK EN EARL.
